UNITED STATES PATENT OFFICE

147,980

DESIGN FOR A PLAQUE

Clinton H. Kratz, Cincinnati, Ohio, assignor to
Cincinnati Metalcrafts, Inc., Cincinnati, Ohio,
a corporation of Ohio

Application March 22, 1946, Serial No. 127,781

Term of patent 14 years

(Cl. D29—23)

To all whom it may concern:

Be it known that I, Clinton H. Kratz, a citizen of the United States of America, residing at Cincinnati, in the county of Hamilton and State of Ohio, have invented a new, original, and ornamental Design for Plaques, of which the following is a specification, reference being had to the accompanying drawing, forming part thereof, in which:

Figure 1 is a front elevational view of a plaque showing my new design, this view showing the outer door closed.

Figure 2 is a front elevational view thereof with the outer door and one of the data-bearing plates swung partially open.

Figure 3 is a side elevational view of the plaque.
I claim:

The ornamental design for a plaque, as shown and described.

CLINTON H. KRATZ.
